UNITED STATES PATENT OFFICE.

PETER M. KLING, OF ST. LOUIS, MISSOURI.

STREET-CAR.

SPECIFICATION forming part of Letter's Patent No. 516,934, dated March 20, 1894.

Application filed August 14, 1893. Serial No. 483,128. (No model.)

To all whom it may concern:

Be it known that I, PETER M. KLING, of the city of St. Louis, in the State of Missouri, have invented a certain new and useful Improvement 5 in Street-Cars, of which the following is a full, clear, and exact description, reference being had to the accompanying drawings, forming part of this specification.

My invention relates to an improvement in 10 the platforms of street-cars; and my invention consists in features of novelty, herein-after fully described and pointed out in the claims.

Figure I is a top view, illustrative of my invention. Fig. II is an enlarged, detail elevation, part in section. Fig. III is a detail view, part in section, and part in elevation; the section being taken on line III-III, Fig. IV. Fig. IV is a detail, top view. Fig. V is an elevation showing the cam and part of the shaft. Figs. VI and VII are detail elevations.

Referring to the drawings, 1 represents the platform of a street or other car. It is divided at each end between the body and the 25 dashboard by a short partition 2, so as to provide for two passage-ways at each side of the car, one, A, for the passengers entering the car, and the other, B, for passengers leaving the car, so that the passengers entering do 30 not interfere with the passengers leaving the car. Each passage-way may be supplied with a turnstile, and the turnstile of passage-way, A, is arranged to operate the usual register on the car. Each turnstile consists of a vertical shaft 3, stepped at bottom into a suitable bearing 4, made fast to the platform, and held 35 at the top by a box or bracket 5, which secures it to the dashboard or to the body of the car, according to the location of the shaft.

On the upper end of the shaft is a head 6, to 40 which a suitable number of arms 7 are pivoted at 8. Beneath the head 6 is a collar 9, having a cam surface 10 for receiving projections 11 on the inner ends of the arms 7. The 45 upper horizontal surface 12, and the lower vertical surface 13 of the collar, also receive the projections 11, as shown in Fig. III. The collar has a shoulder 14, preferably inclined slightly, to prevent retrograde movement of 50 the arms, while permitting them to move gently from a vertical to a horizontal position. The collar 9 is rigidly secured to the body of

the car, or the platform, and the shaft 3 passes through it, as shown in Fig. V. The shaft 3, at the entrance A, is connected by any suitable means to the usual car register, or to a register specially provided for the purpose. I have shown the shaft provided with a notched collar 15 see Fig. II, adapted to operate upon one end of a pivoted bell-crank-lever 16, which is connected by a cord 17 to the register, the register not being shown.

The operation is as follows:—As a passenger gets onto a car, at A, he moves the arm 7 in front of him, turning the shaft 3 partly 55 around, and operating the register once, and as he passes through, he moves the next arm 7 in front of the passage-way of the platform, so that the next passenger will again turn the shaft, and again operate the register. When 60 a passenger is getting off, at B, he turns the stile in the same manner, and as neither stile can be turned backward, on account of the abrupt incline at 14, passengers cannot get on at B, nor off at A. By pivoting the arms 75 7 to the head 6, they are automatically raised to a vertical position by the cam surface 10, to permit them to pass the car body or the dashboard of the car, as they come around to either of these objects, and then they drop 80 again into a horizontal position, after passing the dashboard or car body in order to obstruct the passage ways A and B.

I have shown a pair of turnstiles at each end of the platform, but it is evident that one 85 end only might be supplied, if one end only is to be used by the passengers getting off and onto the car, and I have shown a rail, by dotted lines at 20, Fig. I, such as would be used in the absence of one pair of the turnstiles.

To prevent the turnstile at A being operated other than by a passenger entering the car, and to prevent a person on the platform from operating the register through means of 95 the turnstile, I provide an automatic lock which holds the stile from being turned, except when a passenger is entering. I have shown this lock as consisting of a plate 21, located over the step at A, and which is secured at its inner edge to a rock-shaft 22, the outer edge of the plate being supported by a spring 23. On the rock-shaft is an arm 24, which engages in notches 25 in the periphery

of the wheel 15, (see Fig. VI.) When the passenger entering steps on the plate 21, he withdraws the arm 24 from the wheel 15, permitting the stile to turn, and when the passenger 5 moves onto the platform, the plate 21 automatically rises and engages the arm 24 with the wheel 15 again, thus locking the shaft of the turnstile. As an additional security against the retrograde movement of the turnstile at B, the shaft of this turnstile may have 10 a disk 3^a located beneath the platform, with notches 3^b in its periphery to receive an arm 26 on a yielding plate 27, located in the platform near its edge, (see Figs. I and VII.) A 15 passenger leaving the car and stepping on the plate 27, would unlock the stile, and when he left the platform, the plate 27 would rise and automatically lock the shaft of the stile by bringing the arm 26 into engagement with 20 the notches of the disk on the shaft.

I claim as my invention—

1. A street car platform having a partition at one end thereof extending transversely of the length of the car, and dividing the platform into two parallel passageways between 25 the car body and dashboard; substantially as and for the purpose set forth.

2. A street car platform having a short partition 2 extending in a direction transversely of the length of the car, and providing separate passageways A, B at one end of the platform, substantially as and for the purpose set forth. 30

3. In combination with a street car, a platform having passageways A, B, at one end 35 thereof and a turnstile mounted in each passageway; substantially as and for the purpose set forth.

PETER M. KLING.
